UNITED STATES PATENT OFFICE.

JOHN KRATOCHVIL, OF MAYWOOD, ILLINOIS, ASSIGNOR TO AMERICAN CAN COMPANY, OF NEW YORK, N. Y., A CORPORATION OF NEW JERSEY.

SAFETY DEVICE FOR PUNCH PRESSES AND THE LIKE.

Application filed May 29, 1920. Serial No. 385,148.

To all whom it may concern:

Be it known that I, JOHN KRATOCHVIL, a citizen of the United States, residing in Maywood, in the county of Cook and State of Illinois, have invented a new and useful Improvement in Safety Devices for Punch Presses and the like, of which the following is a specification.

This invention relates in general to feeding mechanism for punch presses and the like, and has more particular reference to feeding mechanism, wherein a strip of sheet metal is fed into a punch press to have a number of articles formed therefrom by successive action of the die parts.

It will, however, be manifest, that with slight changes, the invention may be used for feeding sheet metal to other forms of punch presses and to other types of machines.

My present invention, however, while usable in connection with other and different apparatus, has more particular reference, particularly as embodied for the purposes of illustration in this specification, to the apparatus shown, described and claimed in application for patent Serial No. 385,203, filed May 29, 1920, by Hugo Schoendelen, for improvements in safety devices for punch presses and the like.

A principal object of the present invention is the provision of mechanism and devices for feeding the metal into operative relation with a press or other apparatus, from which articles are delivered into a chute, or other receptacle or delivering mechanism, so constructed, arranged and controlled, that the feeding action will cease when the conditions in the chute, receptacle or other delivering or receiving device, are unfavorable for further action of the press or apparatus. My invention contemplates in this connection, a provision of means for rendering the active feeding part inoperative or without effect, when the chute is clogged or the receptacle too full to receive additional articles.

Numerous other objects and advantages of the invention will be apparent, as it is better understood from the following description, which taken in connection with the accompanying drawings, discloses a preferred embodiment thereof.

Fig. 1 is an end elevation of a press equipped with my invention;

Fig. 2 is a front elevation thereof; and Fig. 3 is an enlarged partial perspective view of a portion of said apparatus.

The apparatus shown on the drawings and selected for the purpose of illustration, is a punch press adapted to form articles such as can ends, from strip material. The strips are automatically fed into a position, from which they may be advanced to the dies, by progressive steps, each step occurring after a die action and being wholly automatic in action. A number of can ends or covers are formed from each strip and the apparatus is so constructed and arranged, that after every descent of the die, a strip is advanced an appropriate distance, to present the part of the strip from which the next article is to be formed. The apparatus also provides for the feeding of the strips in such manner as to cause them to be taken singly from the stack and to follow each other closely past the dies, so that the dies may reciprocate continuously and without interruption.

In this action, the strips are picked up from the dies by suction heads, which arrange them opposite a slot into which they are thrust sidewise by pusher blocks. Arriving in the slot, each sheet is fed forward with a step-by-step movement between the dies. Means are provided in the apparatus for preventing the feeding to the die, should more than a single blank be positioned in the slot, and to stop the feeding action under other adverse conditions.

The apparatus comprises a support 11, carrying a press bed or frame 12, in which are mounted the operative parts. The bed extends up at one side to provide the two standards 13, providing the guides 14, for the upper reciprocating die head 15. At the top, these standards are provided with bearings 16, for the shaft 17, which is the main power shaft and which carries the pulley 18 to actuate the apparatus. The shaft 17 is a crank shaft having a crank 17' and the die head 15 is moved up and down between the guides by the action of said crank in the usual manner. A stack holder 19 is positioned on the bed and at a side thereof and is adapted to contain a stack of blanks or strips to be operated upon, such blanks or strips being indicated at 21. These blanks are lifted or moved singly from the stack by three suction heads 110

22, mounted upon the end of reciprocating rods or pipes 23, axially movable through bearings 24, extending up from the bed. The pipes 23 are connected by pipes 24' and 5 couplings 25 to form a unitary structure and the pipes 23 and 24' and the couplings 25 are hollow and in communication through a valve structure 26, with a vacuum or exhaust pipe 28. The valve 26 is controlled by 10 a slide rod 29, positioned on the right hand suction head and operable by a sheet, when the head contacts therewith, to open the exhaust valve by upward movement of a rod 31. The suction mechanism just described, 15 is caused to reciprocate by a link 32, having a slot 33 in its upper end engaged by a pin 34, upon a lever 35, pivoted at 36, from the bed and connected by a link 37, with a crank disk 38 fixed upon a stub shaft 39. 20 This shaft also carries a gear 41, meshing with a pinion 42, upon a stub shaft 43 and driven by a gear 44, meshing with a pinion 45, upon shaft 17. The gearing is so constructed, that the suction heads move down 25 to pick up a sheet or strip 21, for each number of die reciprocations needed in the formation of the number of articles formed from the strip.

The suction heads carry the strips into 30 registration with a feed slot, into which the strips are pushed edgewise by reciprocating pusher blocks 46. These pusher blocks are mounted upon rods 47, having bearings at 48, extending up from the bed. 35 Reciprocation is imparted to the push rods from a shaft 49 through arms or links 51. The shaft 49 is mounted in bearings 52, and is connected by an arm 53 and the link 54, with a bell crank lever 55 pivoted on the 40 stud shaft 36. This lever carries a roller 56 engaging the cam 57 on the shaft 39, the roller being held against the cam by a spring 58, which spring actuates the pusher blocks in the operative stroke.

45 Thereafter, the sheets are fed along the slot and between the dies, by mechanism which need not be described in detail, since it forms no part on my present invention. It may be mentioned, however, that this 50 mechanism is driven from a crank disk 61 and connecting rod 62.

After the articles are formed by the dies, they are fed into a receiving chute or receptacle 63, and may be seen in Fig. 3, where 55 reference character 64 indicates the formed can end, produced in the present instance. Means are provided in accordance with my invention, to cause the feeding action to cease, when the articles or ends clog the 60 chute and pile up to an extent to interfere with the die action. The pusher block shafts 47 are provided with blocks or stops 65 and the arms 66 are pivoted upon the bearings 24 to normally rest on the shafts 47 65 and behind the stop blocks 65. On each bearing is also provided a rod 67, slidable in bearings 68 by a sheet or strip lifted by the suction head. These rods carry collars 69, adapted to engage under the arms 66 and lift them out of the way of the stop blocks 65 when a strip is in proper position to be pushed into the slot. Should either end of the strip be deformed or not picked up, the arm will not be lifted and both pusher blocks will be prevented from being 70 moved on a pushing stroke under the action of the spring 58. The rods 67 are rather safety device rods, provided to take care of special conditions since the suction heads all being in communication internally, the breaking of the suction at any head prevents application of the suction of the others. The rod 67 at the left of Fig. 2 is provided to push the sheet from the suction head and prevent action of the 75 pusher under certain feeding conditions, which, since they form no part of my present invention, are not thought to require explanation. The rod at the right in this figure and shown in enlarged perspective on Fig. 3, is provided to break the suction at the right hand suction head, and to prevent the lifting of the right hand arm 66 if the press is clogged. A lever 70 is pivoted at 70' on the left hand bed or frame standard 95 and has one end 71 extending over the chute and adapted to be lifted when the articles formed pile therein. The other end 72 extends over and above the upper end of the rod 67 and prevents this rod being lifted 100 by a sheet 21 as the result of the action of the suction heads.

When the lever is in normal position, i. e., when the end 71 which is heavier is in lower position, the rod 67 moves upward in the 105 position shown in Fig. 3, as the sheet approaches the slot, the collar 69 lifting the lever 66 out of the way of the stop block 65. When however, the chute is clogged, the lever 68 prevents movement of the rod 67, 110 pushing the sheet away from the suction head as the suction head approaches the upper end of its stroke, thereby permitting also the arm 66 to rest in position behind and in the path of the stop block 65. This prevents any feeding of the sheets into the slot, until the chute is clear and the parts are so dimensioned and arranged that this interruption of the feeding action will occur 115 while the chute may still receive the additional articles to be formed by the strip or strips already within the slot.

It is thought that the invention and many of its attendant advantages will be understood from the foregoing description, and 120 it will be apparent that various changes may be made in the form, construction and arrangement of the parts without departing from the spirit and scope of the invention or sacrificing all of its material ad- 125 130

vantages, the form hereinbefore described, being merely a preferred embodiment thereof.

I claim:

5. 1. In a feeding mechanism for die presses and the like, the combination of a feed way, a stack of blanks arranged adjacent said feed way, means for feeding blanks to the press, means for discharging formed articles 10 from the press, and means operable by articles in the discharge means for preventing feeding action when the discharge mechanism is clogged, said discharging means having walls within which the die-formed articles are collected and are caused 15 to accumulate in a pile of increasing height in case of any obstacle to the taking away of said articles.
2. In a feeding mechanism for die presses 20 and the like, the combination of a feed way, a stack holder adjacent thereto, means for transferring blanks from said stack to said feed way, a discharge device from the press, and means operable by articles in the discharge device for preventing the action of 25 said transferring means when the articles in said discharge device prevent free discharge from the press, said discharge device having article-confining walls within which the die-formed articles are collected and are 30 caused to accumulate in a pile of increasing height in case of any obstacle to the taking away of said articles.
3. In a feeding mechanism for die presses 35 and the like, the combination of a stack holder for blanks, means delivering blanks singly from said stack holder, a chute for collecting finished articles and having upwardly extending walls to contain said articles in a pile, and means over said chute and operable by finished articles accumulated 40 therein for interrupting said feeding means.
4. In a feeding mechanism for die presses 45 and the like, the combination of a stack holder for blanks, suction means selecting blanks singly from said stack holder and moving them into position to be fed between the dies, a chute for collecting finished 50 articles and having upwardly extending walls to contain said articles in a pile, and means over said chute and operable by finished articles accumulated 55 therein for reducing said suction means.
5. In a feeding mechanism for die presses and the like, the combination of a stack 60 holder for blanks, means singly selecting blanks from the stack holder, a chute for collecting finished articles and having upwardly extending walls to contain said chute and operable by finished articles accumulated 65 therein for separating a blank from said selecting means.
6. In a feeding mechanism for die presses 70 and the like, the combination of a stack holder for blanks, means selecting blanks from the stack, and feeding them, a chute for collecting finished articles and having upwardly extending walls to contain said chute and operable by finished articles accumulated 75 therein for obstructing the feeding movement.
7. In a feeding mechanism for die presses 80 and the like, the combination of a stack holder for blanks, suction means for selecting blanks from the stack, devices for feeding the selected blanks and means pushing the blanks from the suction means and 85 positively obstructing the feeding movement when the delivery from the press is clogged.
8. In a feeding mechanism for die presses 90 and the like, the combination of a stack holder for blanks, a reciprocating suction head for lifting the blank from said stack holder, a rod movable by the blank, when lifted by the suction head, and means operable by accumulated articles formed by the press, for preventing movement of the 95 rod and resulting in separation of the blank from the suction head.
9. In a feeding mechanism for die presses 100 and the like, the combination of a suction head for moving the blanks into feeding position, a member movable by the blank, while carried on said suction head, and means operable through the agency by accumulated articles formed by the press, for preventing movement of said member to cause separation of the blank and suction head.
10. In a feeding mechanism for die presses 105 and the like, the combination of a stack holder for blanks, reciprocating means for moving the blanks in the feeding action, a member positioned in the path of movement of said reciprocating means and lifted out of the way thereof in the normal feeding action, and means operable through the 110 agency of accumulated articles formed by said press, for preventing the lifting of said member.

JOHN KRATOCHVIL.
